UNITED STATES PATENT OFFICE.

GEORGE FEY, OF TAMAQUA, PENNSYLVANIA.

CONCRETE BLOCK MAKING.

Application filed October 6, 1925. Serial No. 60,714.

To all whom it may concern:

Be it known that I, GEORGE FEY, a citizen of the United States, residing at Tamaqua, in the county of Schuylkill and State of Pennsylvania, have invented certain new and useful Improvements in Concrete Block Making, of which the following is a specification.

This invention relates to methods and apparatus for producing concrete or other moulded forms or blocks.

Among the objects of this invention is to provide apparatus which is particularly adapted for the purpose of making moulded forms such as concrete blocks and the like.

Another object of this invention is to provide a novel process for making moulded articles such as concrete blocks wherein the time and labor involved shall be reduced to a minimum and only the simplest apparatus required in the performance thereof.

More particularly my invention provides apparatus for moulding concrete blocks, which apparatus can be used again and again indefinitely and which makes the removal of the solidified forms especially easy, my novel process providing in connection with said apparatus an easy and effective way for moulding and removing the finished article from the mould.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a plan view showing my apparatus in set up position ready to receive the concrete.

Fig. 2 is a side elevation of the same.

Fig. 3 is a sectional view on the line 3—3 of Fig. 4 showing a different position of the apparatus.

Fig. 4 is a plan view of the apparatus in open position and with the mould in section.

Fig. 5 is a sectional view on the line 5—5 of Fig. 2.

Fig. 6 is an enlarged view of the catch mechanism.

Fig. 7 is a similar view showing the catch 55 in a different operative position.

Fig. 8 is a perspective view showing a concrete block made with my apparatus.

Referring now more specifically to the drawings I show my invention as comprising a box form, or mould having removable side and end walls 10 and 11 as well as a removable bottom 12. The members constituting these parts are preferably wholly separable from each other to facilitate the process, but any other arrangement may be employed which will permit the box to be readily demounted for the removal of a block that has solidified therein.

Means are provided co-operating between adjacent side walls to retain said walls in predetermined relation with each other as desired and to facilitate the setting up of the mould to receive the concrete. Said means constitute generally a locking device 70 which is made effective through the operation of internal pressure of the concrete against the walls of the mould. More specifically, it will be seen that the end walls are provided with a plurality of spaced members, one of which is a bar 13 which is rigidly secured at the edges of said end walls and extends along the entire length thereof, the other of said members 14 being positioned

inwardly of the bar 13 so that the end portion of a wall 10 is received between said bars whereby the walls 10 and 11 are retained in predetermined relation with respect to each other. Preferably the bar 14 extends across the wall 11 transversely of the mould and in such manner as to form a groove in a block of concrete which is moulded therein, said groove being utilized in a manner well known in the building art for the purpose of forming a stronger hold 85 between adjacent blocks of concrete as by pouring cement into communicating grooves between adjacent blocks. It will be observed that the locking bars or members are preferably secured upon the end walls 11 to 100 render the locking action more efficient. In other words, since the total pressure upon the side walls 10 of the mould due to the plastic concrete within the mould is greater than the pressure upon the end walls 11 because the area of the latter is considerably less than that of the side walls, it follows that it is most desirable to have the more posi-

tive action of the locking device such as is provided by the bars 13 which prevent any possibility of outward movement of the walls 10 acting as aforesaid. The locking device 5 described is intended to be operative after the concrete has been poured into the mould and put aside to permit the concrete to set. Mechanism to be described hereinafter is used in conjunction with the mould to provide 10 an absolutely secure and rigid engagement between the walls thereof while the concrete is being poured and during such other operation as may be desired to form a thoroughly uniform and cohesive concrete 15 block.

The mould is provided with any suitable means for forming a design upon the block or for forming grooves or ridges as may be desired to facilitate the use of the block in 20 various ways well known to the building art. Thus bars 15 are arranged to extend along the side walls 10 of the mould to form corresponding grooves in the concrete block. Any number of the bars 14 may be provided 25 along the end walls. Preferably a plurality of them is used as shown. One of the end walls is provided with a groove 16 extending thereacross in opposite relation to one of the bars 14 upon the opposite end wall of 30 the mould so as to provide a ridge upon the concrete block which is to interlock with a corresponding groove in an adjacent concrete block when the blocks are used in the normal manner for building purposes. A 35 rubber pad 17 or the like is provided upon the bottom 12 of the mould and preferably secured rigidly thereto, said rubber pad being formed with any suitable design. A concrete block which is formed in the mould 40 will when solidified have an exact duplicate of the design formed upon the pad. Other artistic effects may be secured as, for instance, by placing a sheet of plate glass into the mould, the plate glass becoming a part 45 of the concrete block when the concrete solidifies. The rubber pad will in that event act as a cushion for the glass plate to prevent injury thereto.

The walls of the mold are re-enforced or 50 strengthened in any suitable manner as by means of the bars 18 secured to the end walls of the mould and extending therealong and the bars 19 similarly arranged upon the side walls of the mould. Likewise re-enforcement means is provided for the bottom 12 of the mould, said means including preferably a plurality of cross pieces 20 and a plurality 55 of bars 21 extending lengthwise of the mould.

60 Any suitable co-operation is provided between the walls of the mould and the bottom thereof to facilitate the making of a tight joint therebetween. Thus said bottom is recessed at 22 along the outer side and end edges thereof, the walls of the mould being

received at the recessed portion. It will thus be seen that the bottom edges of said walls are slightly lower than the upper surface face of the bottom of the mould.

Means are provided to co-operate with 70 said mould or box to retain the members aforesaid reliably in position for moulding a block and especially during such time as the concrete is poured into the mould and other operation performed for securing a 75 block of the maximum strength, said means being readily disengageable from the box to permit the box to be set aside while the concrete hardens, and to receive another mould or box for the formation of another block, 80 all in due course as will now be described.

Said means thus constitute a supporting device having members bearing movably against the walls of said mould, and more specifically, comprising movable end and side members or abutments 23 and 24 and a bottom member 25. Said abutment members are movable in any manner that may be desired for the purpose of retaining the movable walls of a mould, such as that described herein or any other kind, in predetermined relation with each other and in position to receive plastic concrete. Said abutment members are so arranged as to receive the mould therebetween and are movable toward each other and toward the walls of the mould so as to lock around the mould. After the concrete has been poured into the mould and the locking device of the mould becomes effective due to internal pressure 90 within the mould as described hereinbefore, the abutment means are moved out of engagement with the walls of the mould so as to permit the mould to be removed from said supporting device and set aside to permit the concrete to harden, said supporting device or machine being then in readiness to receive another mould for the formation of another concrete block. Preferably, especially for the sake of simplicity, said abutment members are secured directly to the bottom member 25 of the machine in outwardly movable relation thereto as by means 95 of the hinges 26 which permit said abutment members to be swung outwardly and downwardly so as to be out of the way when it is desired to remove the mould.

Means is provided for causing said abutment members to bear against the walls of the mould as set forth hereinbefore, said means taking preferably the form of a plurality of locking or catch devices 27 which are operative between adjacent abutments as, for instance, near the corners of the mould. Said catches 27 are mounted upon the side abutments 24 and co-operate preferably with the projecting members or bars 28 which are rigidly secured to the end abutments 23. The side abutments 24 are provided with grooves 29 extending along the 100

edges of said abutments and in position to receive the bars 28. More specifically, the abutments extend along the walls of the mould and into contact with each other 5 forming corners at which the bars and grooves 28 and 29 are positioned. Said abutments are made in any manner desired, but preferably the side abutments 24 comprise a plurality of bars 30 and 31, the latter whereof is longer than the former and is positioned outwardly of the bar 30 whereby the grooves 29 are formed due to the shorter length of the bars 30. Re-enforcement means is provided to act in conjunction 10 with the abutment means as, for instance, plates 32 which are secured to the side abutments and also act as additional spacing means in conjunction with the bars 19 between said abutments and the side walls 15 of the mould to afford a uniform bearing action upon said side walls of the mould. While the abutments may be of any suitable size, they are preferably formed so as to extend below the top of the mould when the 20 apparatus is set up so as to facilitate the formation of a perfectly smooth and uniform surface for the concrete block at the top of the mould or for such other operation as may be desired. Bars 28 in the 25 grooves 29 provide a positive interlock to prevent outward movement of the side abutments when the end abutments are retained in locked relation by the catches 27. However, the catches 27 are particularly adapted 30 for rapid and easy operation and comprise spring actuated members 33 which are pivoted to the anchor or supporting member 34 at 35. The anchor member 34 is secured directly to the side abutments as by means of 35 flanges 36 and retains the member 33 in projected relation so as to bear against the end abutments. A spring 37 is provided which is secured at one end to said movable member 33 and at the other end to an arm 38 40 rigidly fixed within the anchor member 34. Rollers 39 are provided at the ends of the 45 movable member 33 to facilitate the operation of the catch. When the catch is in the position shown in Fig. 6, the spring 37 operates 50 to cause the member 33 to bear against an end abutment. However, when the operator desires to open up the machine for the removal of the mould, he will merely pull open one of the end abutments, thus 55 causing a force to act upon the movable member 33 at the roller 39 as shown by arrow *a*, causing said member to pivot about the pin 35 and swing into the position shown in Fig. 7 beyond dead center so that the 60 spring is operative to retain said member against accidental movement. When it is desired to close the machine, the operator will merely raise the side abutments 24 and then the end abutments so that the latter 65 will strike against the end 40 of said mov-

able member as shown by the arrow *b*, overcoming the force of the spring and causing the member to snap back into the position shown in Fig. 6.

To facilitate the removal of the mould from the machine rollers 41 are provided set within the grooves 42 in the bottom 25 of the machine so that the long bars 21 will ride upon said rollers and permit the mould to be readily removed. Furthermore, an 70 end abutment is so arranged with relation to the bottom 25 of the machine that when opened it provides an incline down which the mould can be readily slipped. Thus the end abutments will be seen as being hinged 75 somewhat below the upper surface of the bottom 25 of the machine, a recess 43 being provided in said bottom to take care of this construction.

Novel co-operation is provided between 80 the bottom 12 of the mould and the holding means provided by the machine. More specifically, the cross pieces 20 and members 21 will be seen to extend somewhat beyond the sides of the mould so as to form the projecting portions 44 and 45 to engage at the recesses 46 which are arranged to lock over 85 said projections. In this way the bottom of the mould is held securely in position and against any possibility of movement especially for a purpose to be described herein-after.

Means is provided for permitting the mould to be tilted while in set up position in the machine, said means comprising preferably a pivot member 47 extending transversely of the machine. Likewise a plurality of members or bars 48 may be provided extending along the bottom of the machine at the ends thereof and acting as 100 stops to limit the tilting movement of the machine about the pivotal member 47. The bars 48 may be formed of any suitable material and arranged in any suitable manner to secure a certain degree of resiliency if desired whereby an easier action and at the same time a quicker return of the machine is secured when the machine is tilted. Preferably I form the members 48 of rubber. My machine likewise comprises anchorage 105 means such as a plate 49 extending wholly along the bottom of the machine and having guide members 50 co-operating with the pivot member 47 to retain the same in relatively fixed position and against unintended lateral movement. Likewise the bars 51 are provided at the corners of the plate 49 to co-operate with the members 48 and insure a uniform and steady tilting of the machine, the members 48 being movable between oppositely positioned bars 51 at an end of the machine. Stop means 52 are secured in movable relation to the machine to limit the stop movement thereof when desired, said stop means comprising preferably bars 115 120 125 130

which are hinged to the plate 49 as by means of the hinges 53. When the stop means 52 are positioned horizontally as shown in Fig. 2, the machine is free for its tilting action. 5 When, however, they are swung into vertical relation they operate to abut against the bottom member 25 of the machine to limit the tilting action. The flat faces 54 at the free edges of the stop members insure 10 that the same will be retained against unintended release or movement as by merely abutting against the bottom 25. Any suitable re-inforcement means may be provided for the bottom plate 49 such as the cross pieces 54 upon which certain of the bars aforesaid are mounted.

My machine provides novel mechanism as has been set forth hereinbefore for facilitating the tilting of a mold after concrete has 20 been poured thereinto. The tilting action is important to provide a concrete block of homogeneous character whereby the maximum strength may be secured, and at the same time to insure that any design that 25 may be desired to be formed upon the block will be reproduced in the most distinct manner possible.

Re-enforced concrete blocks can be made in my machine by embedding metal rods in 30 the concrete in course of moulding the blocks.

I claim:

1. In mechanism for moulding concrete blocks, the combination of a mould having 35 movable walls, and supporting means for the mould comprising abutment members for holding the walls of the mould from movement and to cause the mould to retain the concrete placed therein, and catches for locking 40 adjacent abutments to each other at the corners of the mould, said catches including movable spring actuated members which are arranged to actuate said abutments toward each other, said catches being opened when 45 a force superior to said springs is exerted on the abutments against which the members bear to move said members out of locking position.

2. Mechanism as set forth in claim 1 50 wherein said supporting means comprises a bottom member to which said abutment members are hinged at the bottom of the mould thus permitting said abutment members to swing outwardly and out of the way 55 of the mould to facilitate removal thereof.

3. The herein described process of moulding concrete blocks comprising the setting up of a mould having wholly removable walls with means for frictionally engaging 60 the adjacent walls, bracing said walls to retain the same in temporarily fixed position, placing plastic concrete into the mould, removing the bracing means to permit the walls of the mould to be retained in position 65 as aforesaid through the frictional locking

engagement which results from the internal pressure of the concrete against the mould and the adhesion of the walls to the concrete, and finally permitting the concrete to set in the mould, the walls whereof drop out of engagement with each other when the concrete has set.

4. In mechanism for moulding concrete blocks, the combination of a mould having separable walls, and means separate from 70 said mould comprising movable members arranged to bear upon said walls to retain the same in engagement with each other and the mould in condition to receive the concrete, said means comprising likewise a bottom member supporting the mould and having a pivot member upon which the bottom can be tilted for shaking the concrete in the mould, a member being provided having a recess to receive said pivot member and a supporting 80 member spaced from said recess and hinged for upward tilting movement to bear against the bottom member and hold the same against tilting movement.

5. In mechanism for moulding concrete 90 blocks, the combination of a mould having a bottom and detachable walls, and supporting means separate from said mould and comprising a bottom for supporting the bottom 95 of the mould and abutment means for bearing against the sides of the mould to cause the same to remain in engagement with each other to receive the concrete, said abutment means being hinged to the bottom of the supporting means, rollers being provided between the bottom of the mould and the bottom of the supporting means to permit the mould to be readily removed from the supporting means when the abutments are 100 swung out of holding position.

6. In mechanism for moulding concrete blocks, the combination of a mould having a bottom and detachable walls, and supporting means separate from said mould and comprising a bottom for supporting the bottom 110 of the mould and abutment means for bearing against the sides of the mould to cause the same to remain in engagement with each other to receive the concrete, said abutment means being hinged to the bottom of the supporting means, a pivot member being provided on the bottom of the supporting means for tilting the mould.

7. In mechanism for moulding concrete 120 blocks, the combination of a mould having a bottom and detachable walls, and supporting means separate from said mould and comprising a bottom for supporting the bottom 125 of the mould and abutment means for bearing against the sides of the mould to cause the same to remain in engagement with each other to receive the concrete, said abutment means being hinged to the bottom of the supporting means, anchor means being provided to support the supporting means and 130

retain the same against lateral movement, pivot means being provided between said anchor means and said supporting means, and stop means to limit the tilting of the 5 supporting means upon the pivot means.

8. In mechanism for moulding concrete blocks, the combination of a mould having a separate bottom and separate walls, and supporting means for the mould comprising a 10 bottom member for supporting the mould, and movable abutments having co-operation with the walls of the mould to retain the same in engagement with each other and the mould in condition to receive concrete, said 15 movable abutments having co-operation also with the bottom of the mould to hold the same snugly against the bottom of said supporting means, said movable abutments being hinged to the bottom member of the supporting means along the edges thereof, catches being provided for securing adjacent abutments to each other to retain the same in holding position to bear upon the mould.

25 9. In mechanism for moulding concrete blocks, the combination of a mould having a separate bottom and separate walls, of supporting means for the mould comprising a bottom member, and abutments hinged there- 30 to at the sides and arranged to be tilted into bearing relation to the walls of the mould to retain the same together, rollers being provided between the bottom of the mould and the bottom of the supporting means, one of

said abutments being so arranged that when 35 tilted outwardly and away from the mould it constitutes an incline down which the mould can be moved with facility from the supporting means.

10. In mechanism for moulding concrete 40 blocks, the combination of a mould having movable walls, and outer supporting means for the mould comprising abutments movable into bearing relation with the walls of the mould to retain the same in closed position, and locking means for said abutments including a bar upon one abutment and a catch upon the adjacent abutment, the abutment having the catch being provided with a groove to receive said bar when the abutments are moved into bearing relation to the mould, said bar serving to prevent an outward movement of the abutment having the catch, said catch serving to engage the other abutment to prevent outward movement 55 thereof and disengagement of the bar and the groove.

11. The combination as in claim 10 where- 60 in the mould is longer than it is wide and the abutment having the groove bears upon a longer wall of the mould, the bar serving as a positive lock therefor, said catch having a spring element to facilitate operation of the catch for locking or unlocking the abutment means.

In testimony whereof I affix my signature.

GEORGE FEY.
